UNITED STATES PATENT OFFICE

2,416,782

ADJUSTABLE V-BLOCK

Paul Valish, Waterbury, Conn.

Application May 12, 1944, Serial No. 535,383

3 Claims. (Cl. 90—59)

1

The invention relates to a shaft support or rest, and more especially to an adjustable V-block for machinists use.

The primary object of the invention is the provision of support, rest or block of this character, wherein the same can be keyed to a machine table, so that a machinist can accurately line a shaft for the truing thereof, without the use of shims or other like parts, and such support, rest or block is susceptible of easy and quick adjustment for the proper setting of the shaft.

Another object of the invention is the provision of a support, rest or block of this character, wherein the construction thereof is unique and novel, it being readily and easily applied and removed to and from the work, and is applicable to varying diameters of shafts for the truing operation thereon.

A further object of the invention is the provision of a support, rest or block of this character, which is simple in its construction, thoroughly reliable and efficient in purpose, strong, durable, compact, serviceable for various kind of work, and inexpensive to manufacture and install.

With these and other objects in view the invention consists in the features of construction, combination and arrangement of parts as will be hereinafter more fully described, illustrated in the accompanying drawings, which show the preferred embodiment of the invention and pointed out in the claims hereunto appended.

In the accompanying drawings:

Figure 1 is an elevation of the device constructed in accordance with the invention.

Figure 2 is a top plan view thereof.

Figure 3 is a sectional view on the line 3—3 of Figure 1, looking in the direction of the arrows.

Figure 4 is a sectional view on the line 4—4 of Figure 1, looking in the direction of the arrows.

Similar reference characters indicate corresponding parts throughout the several views in the drawings.

Referring to the drawings in detail A designates generally the support, rest or block constructed in accordance with the invention and hereinafter set forth in detail.

The support, block or rest A comprises a solid base 10, having at the lower flat faced portion centrally thereof in a longitudinal direction a key 11 for fitting in the slot in a machine table (not shown). Upon this base 10 is built a boxing including the vertical side walls 12, which are of uniform height with respect to each other and meet the upper face of the said base 10, while at right angles to the said side walls are end walls

13, these being united to the side walls in any suitable manner, and have their lower edges elevated from the upper face of the base. The upper edge of the end walls 13 have provided therein horizontally aligned V-shaped notches 14 opening upwardly therefrom.

The inner surface of the side walls 12 are beveled as at 15 so as to converge in one direction toward each other, and between the side and end walls 12 and 13 is created a well 16 in which is loosely fitted a centering lifting jack including a turn screw 17 threaded centrally in an adjustable bearing head 18, which is V-notched in its upper face for accommodating upwardly divergent rest or contact plates 19, these being V-set corresponding to the notch or crotch 20 in the said head 18 for the support or resting of a shaft (not shown) to be trued in a truing machine which is also not shown in the drawings.

The meeting faces of the head 18 conforms to the inner surfaces of the side and end walls 12 and 13 of the well 16 created by the boxing. The screw 17 has its lower spindle end 21 displaceably fitting a recess 22 in the base 10 provided therefor. This recess 22 allows for the centering of the head 18 when supporting a piece of work, as for example a shaft, in the truing thereof.

Next to the spindle end 21 of the screw 17 is integrally formed thereon a peripherally socketed turning rim 23 so that a pin or bar can be selectively engaged with a socket therein for the easy turning of the screw in the adjustment of the head 18 to raise and lower the same for the lifting or lowering of the work held thereby.

Tapped centrally in the end walls 13 are horizontally arranged set screws 24, wrench engageable, and one of these screws 24 plays against a gripping plate 25 countersunk in the end wall 13 next thereto, and this plate 25 has contact with the head 18, the plate 25 being held from dropping or displacement by retaining pins 26 from its seat in a vertical direction.

The rim 23 is accessible through openings 27 between the base 10 and the end walls 13, so that the screw 17 can be regulated in the adjustment of the head 18, and such access is had with respect to either end of the support, rest or block.

Many times in a machine shop shafts having a number of unequal diameters or dimensions have to be machined. The machinist has to set the shaft in a V-block or blocks and line up the shaft by placing shims under one or the other end of such shaft.

The shims may be one-fourth or one-half inch scrap steel, tin or mere paper, a very flimsy but

common method, used in some of the best shops, so by using the device herein described, this method is entirely eliminated.

The device is always locked in place centrally, and it can be keyed in the machine table slot with which the said device is used.

The sides and ends 12 and 13 are preferably united together by fasteners 28, while the plates are secured in position with respect to each other by fasteners 29, respectively.

From the foregoing it is believed that the construction and manner of use of the device will be clearly understood and therefore a more extended explanation has been omitted for the sake of brevity.

Changes, variations and modifications may be made in the invention as fall properly within the scope of the claims hereunto appended, without departing from the spirit of the invention or sacrificing any of its advantages.

What is claimed is:

1. A structure of the kind described, comprising a box-like body having inner converging side walls and end walls having their lower ends elevated above the lower ends of said side walls thereby forming a well opening upwardly therefrom, a screw jack fitted within the well, and a V-notched head conforming to the interior of said body threadably connected to the jack and having contacting plates lining the notch therein.

2. A structure of the kind described, comprising a box-like body having inner converging side walls and end walls having their lower ends elevated above the lower ends of said side walls thereby forming a well opening upwardly therefrom, a screw jack fitted within the well a V-

notched head conforming to the interior of said body, contacting plates lining the notch therein, and means carried by the body for acting on the head for centering same.

3. A structure of the kind described, comprising a box-like body having inner converging side walls and end walls having their lower ends elevated above the lower ends of said side walls thereby forming a well opening upwardly therefrom, a screw jack fitted within the well a V-notched head conforming to the interior of said body included in the jack and having contacting plates lining the notch and means carried by the body for acting on the head for centering same, and a gripper for the head coacting with said means.
